(57) **CLAIM**

The ornamental design for a wall-mountable control device with illuminable feature, as shown and described.

DESCRIPTION

FIG. 1 is a front isometric view of a wall-mountable control device with an illuminable feature, under a first embodiment.

FIG. 2 is a frontal view of FIG. 1.

FIG. 3 is a frontal view of a wall-mounted control device having an illuminable feature, under a second embodiment; and,

FIG. 4 is a frontal view of a wall-mounted control device having an illuminated feature, under a third embodiment. The broken lines in the drawing depict environment and form no part of the claimed design. The illuminable feature shown in FIG. 4 is shaded for translucency.

1 Claim, 4 Drawing Sheets
